VENDING MACHINE

Frank Payne, Etowah, Tenn.

Application April 15, 1939, Serial No. 268,032

6 Claims. (Cl. 312—89)

My invention relates to new and useful improvements in vending machines.

An important object of my invention is to provide a vending machine that is adapted to contain a plurality of small articles such as aspirin, gum or the like, and to individually or seriatim discharge the same to the customer.

Another object of my invention is to provide a vending machine that is light and compact in its construction, and that may be placed in any convenient location that is readily accessible to potential customers.

Still another object of my invention is to provide a vending machine that is adapted to operate upon the deposit of a coin in the device and that will automatically return the desired article to the customer.

Another object of my invention is to provide a vending machine that will require very little supervision or attention after it has been filled with the articles to be vended.

A further object of my invention is to provide a vending machine that is simple in construction, efficient in operation and inexpensive to manufacture.

Other objects and advantages of my invention will be apparent during the course of the following description.

In the drawings, forming a part of this specification, and in which like numerals are employed to designate like parts throughout the same—

Figure 1 is a vertical sectional view of a device embodying my invention,

Figure 2 is a longitudinal sectional view taken on the line 2—2 of Figure 1,

Figure 3 is a transverse sectional view, taken on the line 3—3 of Figure 2, and showing parts broken away,

Figure 4 is a front elevation of my device, and

Figure 5 is a top plan view of the agitator plate embodying a part of my invention.

In the accompanying drawings, wherein for the purpose of illustration, is shown a preferred embodiment of my invention, the numeral 10 designates a box-like receptacle which includes a base member 11, rear and front walls 12 and 13, side walls 14 and 15, and a removable cover 16. The supporting blocks 17 and 18 are mounted interiorly of the box and in appressed relation with the inner face of the sides 14 and 15. The upper face 19 of the block 17 is bevelled toward the inside of the receptacle, and the upper face 20 of the block 18 is similarly bevelled but at a greater angle so that the inner rectilinear edge 21 of the

face 20 is disposed substantially lower than the corresponding rectilinear inner edge 22 of the block 17.

A slug proof coin slide 23 of conventional construction, is carried by the front wall 13 of the receptacle and the slide bar 24 thereof operates interiorly of the receptacle. The upper portion of the block 18 is of reduced thickness to define the longitudinally extending horizontal shoulder 26 and the inner face of the projecting lower portion 27 thereof is provided with an angularly disposed groove 28 the upper end of which opens through the shoulder 26 substantially one-third of the way from the rear wall 12, and the lower end thereof communicates exteriorly of the receptacle through the front wall 13. The basin 29 is carried by the base 11 under the outlet end of the groove 28 to receive the vended articles discharged therethrough. The cover plate 30 is carried by the block 18 and encloses the inclined groove 28.

The discharge plate 31 is carried by the inwardly extending end of the slide bar 24 and has one longitudinal edge slidably received within the recess 25 in the block 17 and the other longitudinal edge supported on the shoulder 26 of the block 18. The rear edge 32 of the discharge plate extends rearwardly of the said slide bar but terminates a substantial distance from the rear wall 12, and an integrally formed lateral tongue 33 extends forwardly along the slide bar and with its forward end 34 normally positioned adjacent the front wall 13 of the receptacle when the slide bar 24 is in the fully retracted position. The lateral recess 35 in the discharge plate is of substantially the same size as the article to be vended, which is here illustrated as an aspirin. The recess 35 is therefore substantially rectangular in shape and is slightly larger than the ordinary aspirin, and when the slide bar 24 is in the innermost or advanced position, the recess 35 is adapted to communicate with the upper end of the inclined groove 28 in the block 18.

An agitator plate 36 is supported by but not attached to the discharge plate 31 and either side thereof slidably engages the inner faces of the blocks 17 and 18. The side 37 of the agitator plate is provided with a lower longitudinal recess 38 which overlies an upwardly extending shank 39 carried by the discharge plate 31. The spaced pins 40 and 41, are carried by the plate 36 and extend laterally through the recess 38 to be alternately engaged by the vertical shank 39 when the slide bar 24 is reciprocally actuated. The upper face 42 of the agitator plate is bev-

elled so that the rectilinear edges 43 and 44 thereof will be positioned in aligning relation with the rectilinear edges 22 and 21 of the blocks 17 and 18. The side 45 of the agitator plate is provided with an elongated recess 46 of substantially the same width as the recess 35 in the discharge plate 31 and of sufficient length to accommodate several of the articles to be vended. Transverse closure walls 47 and 48 are positioned above the agitator plate 36 and are supported in aligning slots in the blocks 17 and 18 to define a central space within the receptacle bounded by the upper face of the agitator plate 36, upper faces 19 and 20 of the blocks 17 and 18, and the top cover 16.

The operation of my device is as follows:

When the slide bar 24 is in the fully retracted, or coin receiving position, the discharge plate 31 will be positioned forwardly in the receptacle 20 and the vertical shank 39 carried thereby will be in engagement with the lateral pin 40 to move the agitator plate 36 forwardly in the receptacle so that the forward edge thereof will be adjacent the front wall 13. The articles to be vended are 25 deposited between the transverse walls 47 and 48, and by virtue of the inclined nature of the upper surface 42 of the agitator plate, several of the said articles will fall within the elongated slot 46. The slot is here illustrated as adapted to accommodate four aspirin, the foremost of which will drop into the aligning slot 35 of the discharge plate 31. When the coin is inserted in the coin slide, the slide bar 24 may be pushed inwardly into the receptacle and the article within the slot 35 will be moved rearwardly until it moves into alignment with the upper end of the inclined groove 28 in the block 18. The vertically extending shank 39 of the discharge plate will engage the rear laterally extending pin 41 of the agitator plate before the recess 35 aligns with the groove 28 to move the said agitator plate a 40 slight distance rearwardly therewith and to jar the same in a manner to cause another of the said articles to be deposited within the elongated slot 46. When the slot 35 in the discharge plate is in alignment with the upper end of the inclined groove 28 it will be disposed rearwardly of the elongated slot 46 in the agitator plate, and the article positioned therein will drop into the inclined groove 28 and roll downwardly therein and into the basin 29. Upon forward movement of the slide bar, the discharge plate will move forwardly in a manner to bring the recess 35 into alignment with the elongated slot 55 46 in the agitator plate to receive another of the articles positioned therein. Shortly before the coin slide is in the fully retracted position the shank 39 will engage the foremost pin 40 of the agitator plate to move the same forwardly and 60 to jar another of the articles into the elongated slot 46.

It may thus be seen that upon full retraction of the slide bar 24, the device will be again fully loaded and ready to discharge another article 65 upon the insertion of another coin in the coin slide. Because of the inclined upper surface 42 of the agitator plate and the jarring motion which it receives upon every actuation of the coin slide, the articles within the hopper will 70 be entirely discharged from the machine before refilling is required.

It is to be understood that the device is not 75 restricted to aspirin, but may be used to vend any small article of uniform size. The form of the invention herewith shown and described is

to be taken as a preferred example of the same, and various changes in the size, shape and arrangement of parts may be resorted to, without departing from the spirit of my invention, or the scope of the appended claims.

Having thus described my invention, I claim:

1. In a vending apparatus, a receptacle having a discharge chute, a discharge plate slidably mounted within said receptacle and having a recess communicable with the said discharge chute, an agitator plate arranged in superposed relation with the discharge plate, said agitator plate being supported by but unattached to the said discharge plate and comprising the floor of a hopper containing articles to be vended, said 15 agitator plate having an elongated slot to receive a plurality of articles to be vended and aligning with the recess in the said discharge plate, actuator means connected to the discharge plate and adapted to reciprocate the same independently of the agitator plate to move the recess into and out of register with the discharge chute, and catch means carried by the discharge plate adapted to engage the said agitator plate during the travel of the discharge plate to shake 20 the articles to be vended into the said elongated slot.

2. In a vending apparatus, a receptacle having a discharge chute, a slide positioned in and operating through one end of the said receptacle, 30 a discharge plate secured to the said slide and formed with a recess adapted to be moved into and out of register with the said discharge chute, and an agitator plate arranged in superposed relation for independent sliding movement 35 on the said discharge plate, said agitator plate comprising the bottom of a hopper containing articles to be vended and acting to close the recess in the discharge plate upon movement of the recess into register with the said discharge 40 chute.

3. In a vending apparatus, a receptacle having a discharge chute, a slide positioned in and operating through one end of the said receptacle, a discharge plate carried by the said slide and 45 slidable therewith and having a recess adapted to be moved into and out of register with the said discharge chute but being normally out of register therewith, and an agitator plate supported by the said discharge plate for independent sliding movement thereon and comprising the floor of a hopper containing articles to be vended, said agitator plate having an elongated slot normally aligning with the recess in the said discharge plate and the upper surface 55 thereof being inclined to direct the articles to be vended into the said elongated slot and recess, whereby actuation of the slide to move the recess in the discharge plate into register with the discharge chute will move the said recess 60 out of register with the elongated slot whereby only the article within the recess will be discharged from the receptacle.

4. In a vending apparatus, a receptacle having a discharge chute, a slide positioned in and operating through one end of the said receptacle, a discharge plate carried by the said slide and slidably therewith and having a recess movable into and out of register with the said discharge chute but being normally out of register therewith, an agitator plate supported by the said discharge plate for independent sliding movement thereon and comprising the floor of a hopper containing articles to be vended, said agitator plate having an elongated slot normally 70 75

- aligning with the recess in the said discharge plate and an inclined top surface to direct the articles to be vended into the said elongated slot and recess, spaced pins extending laterally from one side of the said agitator plate, and a vertically disposed pin projecting from the said discharge plate intermediate the said first pins and adapted to alternately engage the first-mentioned pins during the actuation of the discharge plate by the slide to shake the articles to be vended into the said elongated slot, actuation of the slide moving the recess in the discharge plate into register with the discharge chute and out of register with the elongated slot whereby only the article in the recess may be discharged from the receptacle.
5. A vending apparatus having in combination a receptacle provided with a discharge chute, a discharge plate mounted for sliding movement 20 within the receptacle and having a recess movable into and out of register with the discharge chute but normally out of register therewith, and an agitator plate arranged for independent
- sliding movement above the discharge plate and having a slot normally in register with the recess, actuation of the said discharge plate acting to move the recess out of register with the slot and into register with the discharge chute. 5
6. A vending apparatus having in combination a receptacle provided with a discharge chute, a discharge plate mounted for sliding movement within the receptacle and having a recess movable into and out of register with the discharge chute but normally out of register therewith, an agitator plate arranged for independent sliding movement above the discharge plate and having a slot normally in register with the recess, actuation of the said discharge plate acting to 15 move the recess out of register with the slot and into register with the discharge chute, and actuator means carried by the discharge plate adapted to engage parts of the agitator plate upon movement of the recess into register with the discharge chute to shake the said agitator plate. 20
